UNITED STATES PATENT OFFICE.

EDGAR P. ELZEY, OF PARKERSBURG, WEST VIRGINIA, ASSIGNOR TO EDWIN L. DAVIDSON, OF PARKERSBURG, WEST VIRGINIA.

SWING-CHAIR.

1,271,453.

Specification of Letters Patent.

Patented July 2, 1918.

Application filed October 2, 1917. Serial No. 194,340.

To all whom it may concern:

Be it known that I, EDGAR P. ELZEY, a citizen of the United States of America, and resident of Parkersburg, county of Wood, 5 and State of West Virginia, have invented certain new and useful Improvements in Swing-Chairs, of which the following is a specification.

This invention relates to certain improvements in swings; and the object and nature of the invention will be readily understood by those skilled in the art in the light of the following explanation of the accompanying drawings illustrating what I now believe to 15 be the preferred embodiment from among other constructions within the spirit and scope of my invention.

An object of the invention is to provide an improved swing chair or seat of an exceedingly simple and durable construction that will be capable of folding or knocking down into compact form for easy and convenient handling, storage and transportation and that can be easily set up for use without requiring skilled or expert assistance and that when set up will be locked in operative position.

The invention consists in certain novel features in construction and in combinations 30 and arrangements as more fully and particularly set forth and pointed out hereinafter.

Referring to the accompanying drawings:—

Figure 1, is a perspective view of my 35 swing set up and locked in operative position, the supporting chains being shown by dotted lines.

Fig. 2, is a perspective view showing the 40 swing folded for storage or shipment.

Fig. 3, is a cross sectional view.

Fig. 4, is a detail horizontal section.

In the particular embodiment illustrated, 45 the chair or swing comprises a main bottom frame to which the seat bottom is secured; upright end pieces or arms pivotally joined to said bottom frame and adapted to fold inwardly and downwardly thereonto and provided with means for attachment to the 50 swing supporting chains; a back pivotally joined to said bottom frame and adapted to fold forwardly and downwardly onto said end pieces when folded, and normally arranged in upright position in rear of said 55 end pieces; and locking devices normally

coupling the back to said end pieces to maintain the parts in operative position and adapted to be swung from operative position joining the back and ends to permit the parts to be adjusted to folded position for storage or transportation, said devices adapted to be locked in operative position by the swing supporting chains.

In the drawings, any suitable seat bottom 60 1, is secured on a horizontal bottom frame consisting of longitudinal front bar 2, rear bar 3, and end cross bars 4, rigidly secured to said longitudinal bars. If so desired, one or more intermediate cross bars may be secured to the longitudinal bars. Short rigid 65 vertical posts 5, are fixed to and rise from the ends of the front bar 2, and corresponding short rigid vertical posts 6, are fixed to and rise from the ends of the rear bar 3; the posts 5, 6, rigid with and located at the 70 corners of either end of the frame being aligned, *i. e.* approximately arranged in alignment with the adjacent end bar 4.

If so desired, a corresponding intermediate short rigid post 6', can be provided 75 rigidly secured to the rear longitudinal bar 3 and rising therefrom.

The foldable back consists of a suitable 80 frame, the members of which are rigidly secured together and to which the slats 7 (or other suitable fillings) are secured. The back frame comprises several cross or upright bars 8, having depending ends pivotally joined to the posts 6, 6'. In the example 85 illustrated, the upper ends of the posts 6, 6', are mortised or bifurcated fore and aft of the chair and the depending ends of back bars 8, loosely fit in said mortises and are pivotally joined to said posts by the several 90 alined transverse hinge or pivot bolts 9.

The folding upright ends or arms of the 95 swing chair are preferably similar in construction and dimensions, and each consists of a fore and aft top piece or arm rest 10, and vertical front and rear depending members 11, the upper ends of which are traversed by the arm rest 10 which is rigidly fixed thereto. These members 11 are 100 arranged between the adjacent front and rear posts 5, 6, and their side faces abut the adjacent side faces of said posts, and their lower ends terminate above the top face of the slats or other seat bottom 1. The ends 105 or arms 10, 11, are pivotally coupled to posts 110

5, 6, by cylindrical hinge or pivot rods 12 supported by the posts. The lower ends of each pair of members 11, are formed with alined bearing holes or perforations 11', 5 through which a rod 12 loosely extends so that said members can turn on the rod.

The rods 12 fit into the posts 5, 6, and extend transversely across the seat at a distance above the bottom thereof. The rods 10 are preferably removably secured in the posts and removably fit in the members 11 of the arms. For instance, I show the front posts 5 formed with sockets 5' removably receiving the front ends of rods 12, while the 15 rear posts 6 are formed with perforations 6" receiving the rear ends of said rods and through which the rods are slipped or inserted in assembling and through which they can be withdrawn when the arms are to be 20 removed. The rods are removably locked in operative position by suitable means such as screws 13 inserted transversely through the posts 6 and into the rear ends of the rods.

The seat back is held in operative upright 25 position with respect to the seat and arms and the arms are also held in operative upright position, by suitable means. For instance, for this purpose, I show vertically-swingable elongated flat metal latches or 30 links 14, at their rear ends pivotally coupled to the end bars 8 of the back by pivots 15, and at their front free ends having transverse slots or notches 16 opening through their bottom edges. The free front ends of 35 these latches are longitudinally arranged in slots 17 in the arm rests 10 extending longitudinally thereof and opening through their rear ends. These slots are traversed by cross pins 18 fixed in said arm rests. The 40 pins 18 enter the notches 16 of the latches when the parts are in operative position and thus hold the back in operative position while the location of the latches in the slots in the arm rests holds the arms in operative 45 position and against lateral swing. The latches extend into the slots with their top edges flush with or below the top faces of the arm rests and hence are out of the way and do not form objectionable obstructions. The 50 latches usually rest on the top edges of the rear members 11 and are thus held against downward movement while the walls of the slots hold the latches against lateral play or movement so that the arms are firmly held 55 and braced against swinging on the rods 12.

Suitable means are provided for attaching the chair supporting chains 20. For instance, I show each arm provided at its front and rear ends, with hook or eye bolts 60 21 for this purpose. These bolts are anchored in the members 11 of the arms and their eyes or hooks 22 project above the arm rests 10. The rear eyes 22 are arranged beside and adjacent to the slots 17 in said 65 rests that receive the latches 14 so that the

attaching links 23 (see Fig. 4) by which the two rear chains 20 are coupled to the two rear eyes 22, will, when in normal chair sustaining position, overhang the latches 14, and act as stops or obstructions against upward swing thereof. These attaching devices 23 of the chains thus serve to lock the latches against such upward swing as will release the latches from keepers or pins 18. When the chains are slack or have been released at their upper ends, the attaching links 23 thereof can be laterally moved or twisted to permit such upward swing of the latches as to release the same from the keepers 18. 70 75 80

When the latches have thus been swung upwardly to release the arms, the arms can be swung inwardly and downwardly to rest on the seat bottom, and the back can then be swung forwardly and downwardly to a position over the arms and approximately parallel with the bottom seat (see Fig. 2) with its free edge resting on the upper ends of the front posts 5. The chair can thus be folded into a small compass for storage or 90 shipment.

The chair can be easily and quickly restored to operative position by swinging the back to upright position, then swinging the two arms upwardly and outwardly to vertical position, and then swinging the latches to their limits of downward movement in slots 17, with keepers 18 located in notches 16 of the latches. 95

It is evident that various changes, modifications and variations might be resorted to without departing from the spirit and scope of my invention and hence I do not wish to limit myself to the exact disclosures hereof. 100

What I claim is:

1. A swing chair comprising a seat, arms pivotally coupled thereto and provided with upwardly projecting means for the attachment of the chair supporting chains, a back pivotally coupled to said seat, and swingable latches between the back and seat, said latches being arranged adjacent to certain of said means and so arranged that the links for attaching supporting chains to said certain means will obstruct releasing swing of 110 said latches.

2. A chair comprising a seat having pairs of front and rear upright posts, removable transverse rods fitted in said pairs of posts, respectively, foldable arms having depending members removably receiving and swingable on said rods, a back pivotally coupled to the rear posts, and latches between the back and arms. 120

3. A swing chair comprising a seat provided with upwardly projecting posts rigid therewith and arranged at the front and rear corner portions thereof, a back pivotally joined to the rear posts to fold forwardly and downwardly toward the seat 125 130

- into engagement with the upper ends of the front posts, ends pivotally joined to the seat and arranged to fold downwardly thereon, and means for detachably holding the back and ends in normal upright positions. 5
4. A swing chair comprising a seat provided with upwardly projecting posts rigid therewith and arranged at the front and rear corner portions thereof, a back pivotally joined to the rear posts to fold forwardly and downwardly toward the seat into engagement with the upper ends of the front posts, arms pivotally joined to the front and rear posts and arranged to fold 10 downwardly onto the seat, and latches for normally holding the back and arms in upright positions.
5. A swing chair comprising a seat provided with upwardly projecting posts rigid therewith and arranged at the front and rear corner portions thereof, a back pivotally joined to the upper ends of the rear posts to fold forwardly and downwardly toward the seat, arms arranged between 15 and at the inner faces of the front and rear posts and arranged to swing downwardly onto the seat, transverse rods carried by the front and rear posts and constituting the pivotal coupling between the 20 arms and posts, and means for detachably holding the back and arms in normal upright positions.
6. A swing chair comprising a seat having pairs of front and rear upright posts, 25 transverse rods supported by and fitted in said pairs of posts respectively, foldable arms coupled to said posts through the medium of said rods, said rods forming the axes on which said arms are swingable onto 30 the seat, a back pivotally coupled to the seat, and means for detachably holding the back and arms in normal upright positions.
7. A swing chair comprising a seat having transverse rods arranged above its end 35 portions, means removably securing said rods to the seat and whereby the seat is supported from the rods, arms arranged to fold downwardly to the seat and removably receiving and swingable on said arms, said 40 arms being provided with means for the attachment of chair supporting chains, a back pivotally joined to the seat, and means for normally maintaining the back and arms in 45 normal upright positions.
8. A swing chair comprising a seat having pairs of front and rear upright posts, 50 transverse rods fitted in said pairs of posts respectively, foldable arms swingable on said rods and coupled thereby to the seat
- and provided with means for the attachment of chair supporting chains, a foldable back, and latches for normally maintaining the back and arms in upright positions. 60
9. A swing chair comprising a seat having upright posts rigid therewith, and arranged at the front and rear corners thereof, a swingable back pivotally joined to the rear posts, swingable arms pivotally joined to both the front and rear posts, and latches 65 for maintaining the arms and back in normal upright positions.
10. In a swing chair, in combination, a seat, arms coupled to the seat to support the same and to fold thereto to inoperative position, each arm comprising an arm rest at its front and rear portions having upwardly projecting eyes for the attachment of the 70 chair supporting and suspending connections and a longitudinal rear end slot arranged beside the rear eye and traversed by a keeper, a back coupled to said seat to fold to inoperative position, and latches coupled to the back and arranged to normally lie in said slots and engage said keepers to 75 maintain the back in operative position, said latches being detached by upward swing past said eyes to release the back for folding. 80
11. In a swing chair, in combination, a seat having pairs of aligned transverse sockets at its end portions, a pair of seat-supporting transverse rods arranged in said sockets and longitudinally movable therefrom, means normally securing said rods 85 against removal from said sockets, seat-supporting arms removably coupled to said rods and adapted to fold to inoperative position, a back coupled to said seat and adapted to fold to inoperative position, and 90 means for normally maintaining the back and arms in operative positions.
12. In a swing chair, in combination, a seat at its opposite ends having aligned transverse sockets, transverse rods arranged 95 in said sockets and longitudinally removable therefrom, chair-supporting arms arranged to swing inwardly to inoperative position and provided for the attachment of chair supporting suspending connections, said arms having transverse holes longitudinally and removably receiving said rods, a back arranged to fold inwardly to 100 inoperative position, and means for normally maintaining the back and arms in 105 operative positions.
